UNITED STATES PATENT OFFICE.

IRVING R. LEDERER, OF PROVIDENCE, RHODE ISLAND.

DESIGN FOR A BRACELET.

Application filed April 13, 1928. Serial No. 26,314. Term of patent 3½ years.

To all whom it may concern:

Be it known that I, IRVING R. LEDERER, a citizen of the United States, residing in Providence, county of Providence, and State of Rhode Island, have invented a new, original, and ornamental Design for a Bracelet, of which the following is a specification, reference being had to the accompanying drawing, forming a part thereof.

I claim:

The ornamental design for a bracelet, substantially as shown.

IRVING R. LEDERER.
